8 Claims. (Cl. 193—35)

1

This invention relates to conveyors adapted more particularly for use in supplying stereo or other printing plates from a foundry to rotary printing presses.

The present method of conveying stereo plates from the foundry to the machine or press room of a printing office is either by means of a conveyor from the foundry to a central point of the machine room or by means of a conveyor which circulates round the machine room, operates on each printing machine taking off the required plates by hand as they pass.

Conveyors of this type run at a low level and at a slow speed in order to keep the safety factor high.

In a printing office where the number of plates to be delivered to rotary presses is large and the distance of travel is great, it is necessary to deliver the plates to many stations at a high speed as the loss of time taken in delivering them from the foundry to the presses must be as little as possible.

To run separate conveyors from the foundry to each station would be costly and maintenance would be very high and impracticable owing to the large amount of space required.

The object of the invention is to provide a conveyor mechanism of the free-roller type, arranged overhead in such manner that if the stereo or other printing plates or the like bodies, which are in the form of segments of hollow cylinders, loaded on to it have been given a sufficient velocity of motion at the commencement of their journey, gravity will maintain their speed until they reach their destinations.

According to the invention, the conveying mechanism comprises a bank of conveyor rollers and one or more offtake chutes making junction with the bank of conveyor rollers and descending therefrom to the various delivery stations located along the conveyor. The bank of conveyor rollers is composed of alternate series of long and short rollers, the long rollers being of a length sufficient to provide separate laterally-overlapped paths of travel for the stereo printing plates which may be selectively placed upon the conveyor at its loading end in staggered out-of-line positions, depending upon the paths of travel the printing plates are respectively intended to follow and the stations to which they are to be delivered, each path of travel corresponding approximately in width to that of a printing plate. The short rollers are located in the vicinity of the junction of the offtake chutes with the bank of conveyor rollers, so that a printing plate may ride without

2

interference off the end of a series of long rollers onto an offtake chute leading downwardly at one side of the conveyor. The short rollers serve to support one edge of the succeeding printing plates intended for delivery to stations located farther along the conveyor, and skids are provided for supporting the opposite edges of such printing plates. The skids bridge the space created by the offtake chutes dipping away from the plane of the bank of conveyor rollers and these skids are suitably provided with gaps to allow the stereo printing plates to pass downwardly along the chute. For guiding the printing plates along their respective paths of travel, guide rails, suitably arranged in pairs for engaging opposite sides of a printing plate, are provided adjacent the bank of conveyor rollers and these guide rails desirably are extended down the chutes. Thus, the stereo printing plates fed onto the loading end of the conveyor may be delivered to selected stations in accordance with the transverse positions in which they are initially placed on the conveyor at the loading end.

The conveyor may include any suitable number of offtake chutes corresponding to the number of delivery stations to be served. After each series of short rollers, that is, following each offtake chute, the conveyor is stepped to a narrower width until at its discharge end it may be of a width corresponding to that of a single path of travel for a stereo printing plate and may lead to the final delivery station.

The conveyor for the greater portion of its length may be slightly inclined downwardly and the offtake chutes may each comprise a continuous series of secondary rollers extending downwardly from the bank of conveyor rollers at a steeper inclination than the conveyor.

The invention will be described in detail and by way of example with reference to the accompanying drawings in which:

Figure 1 is a view in elevation illustrating somewhat diagrammatically a conveyor arrangement for delivering printing plates to four stations;

Figure 2 is a larger fragmentary view, in side elevation, of a portion of the conveyor;

Figure 3 is a plan view of a portion of the conveyor;

Figure 4 is an end view of the conveyor indicating the disposition of the printing plates thereon; and

Figure 5 is a detail view of the conveyor in transverse cross-section showing the manner in which a printing plate engages a guide rail.

In Figure 1 of the drawings is diagrammatically illustrated the general arrangement of a conveyor constructed in accordance with the invention for supplying segmental-shaped printing plates 4 to four different delivery stations.

The conveyor comprises a bank of conveying rollers arranged in series so as to constitute a generally horizontal portion 1 of the conveyor, and leading downwardly from the plane of the conveying rollers and terminating at the respective delivery stations are offtake chutes 2 comprising separate series or banks of rollers 6.

The conveying rollers, as best shown in Figure 3, are arranged in alternate series of long rollers 3 and short rollers 5 with a series of short rollers 5 extending between the gap separating two adjacent series of long rollers 3. Each offtake chute 2 is inclined steeply downwardly from a side of the conveyor at a location beyond the ends 5a of a series of short rollers 5, so that a printing plate 4 riding down a chute in the gap between the series of long rollers clears the ends of the short rollers, as indicated in Figure 3.

The long rollers 3 are of a width representing a plurality of laterally overlapped paths of travel of the printing plates, the width of the path of travel of a printing plate corresponding approximately to the width of the printing plate, or the distance between its two roller-contacting edges. The length of the long rollers 3 (measured widthwise of the conveyor) of a series of long rollers following a series of short rollers 5, considered in the direction of feed of the conveyor, is somewhat shorter than that of the series of long rollers preceding the same series of short rollers. That is to say, the several series of long rollers 3 are progressively "stepped back" in length in the direction of advance of the conveyor. This follows from the fact that, since each path of travel of a printing plate along the conveyor terminates at an offtake chute 2, the combined overlapped paths of travel for the remaining printing plates intended for delivery to stations located farther along the conveyor become progressively narrower beyond the several offtake chutes, until the width of the rollers 3 leading to the chute 2a to the final delivery station corresponds approximately to the path of travel of a single printing plate.

Similarly, the several series of short rollers 5 are progressively stepped back in length to the same extent as the long rollers 3 to correspond to the narrowing width of the conveyor in the direction of its length.

Extending lengthwise of the conveyor and along the offtake chutes are guide rails 7 arranged in laterally overlapped or staggered pairs, with each pair of guide rails defining a path of travel for a printing plate. These guide rails are supported on transverse structural members 8 and are so positioned that diametrically opposite edges of the plates are engaged by the rails to retain them in their laterally offset or staggered relationship and to insure that the plates will be delivered to their proper stations.

Bridging the gaps between successive series of long rollers 3 are parallel-arranged skid plates 9, the construction and arrangement being such that those printing plates traveling to more distant stations along the conveyor will have one of their edges supported on the short rollers 5 and the other of their edges supported on one of the skid plates 9.

In order to allow a printing plate 4 to roll down one of the chutes 2 to a delivery station without

obstruction, the skid plates are interrupted intermediate their lengths to provide a small gap or clearance 10 to pass the printing plate therebetween.

5 In the operation of the conveyor just described, the stereo printing plates are loaded onto the conveyor at its receiving end and are guided along their respective paths of travel by the guide rails 7. Depending upon the position laterally 10 of the conveyor in which the printing plates are loaded onto the conveyor, the printing plates will be selectively guided to the desired delivery stations. The printing plates will travel along the conveyor rollers guided by the guide rails 9 15 and pass over the gaps between successive series of long rollers 3 with one edge of the plate supported on the short rollers 5 and its other edge supported on a skid plate 9, both short rollers and skid plate being located in the plane of the conveyor. When the printing plate nears the delivery station to which it has been consigned, both edges of the printing plate will pass off onto the rollers 6 constituting the offtake chute 2 and, owing to the steep inclination of this chute, will be impelled by gravity to the delivery station.

The width of the conveyor becomes progressively narrower in stages between succeeding offtake chutes so that ultimately the long rollers 3 narrow down to approximately the width of the path 30 of travel of a single printing plate. Thus, a printing plate destined for delivery at the final station rolls off the steeply inclined conveyor rollers constituting the offtake chute 2a at the terminal end of the conveyor.

35 By virtue of this construction the printing plates may be conveniently and speedily delivered from the foundry to any selected one of a plurality of stations located at various locations in the printing machine plant.

40 The conveyor may be of the free-roller type or partly of the free-roller type, but provision may be made for driving all or certain of the rollers to effect the conveying operation. Provision may also be made for braking certain of the 45 rollers and particularly those which form relatively steeply inclined parts of the conveyor system.

While the invention has been particularly described with reference to the conveying of printing plates, it is equally adapted for use in the supplying of other objects in the form of segments of hollow cylinders and the like.

We claim:

1. A conveyor for delivering segmental-shaped articles such as stereo printing plates to stations located at different distances along the conveyor, said conveyor comprising a continuous bank of article-supporting conveyor rollers consisting of alternately occurring series of long and short rollers, the long rollers being of a length corresponding to the width of a plurality of laterally-overlapped paths of travel for the articles arranged in successive, out-of-line positions on the conveyor, a plurality of offtake chutes leading to delivery stations located at various distances along the conveyor, said offtake chutes each making junction with an end of a series of long rollers and inclined downwardly at one side of the conveyor to a delivery station, said chute being disposed clear and beyond the ends of the adjacent series of short rollers, skid members extending in the plane of the bank of conveyor rollers and overlying the chute for bridging the space between alternate series of long rollers in such manner that the skids and short rollers provide

support for opposite sides of onwardly traveling articles intended for delivery to more distantly located stations, said skid members being provided with gaps to afford passage for the articles moving downwardly along the chute, and guide means extending along and adjacent the bank of rollers adapted to engage and direct the articles along their respective paths of travel.

2. A conveyor as set forth in claim 1 wherein the bank of conveyor rollers extends downwardly at an inclination from the loading end of the conveyor towards its discharge end for the gravitational travel of the articles therealong.

3. A conveyor as set forth in claim 1 wherein the offtake chute comprises a series of rollers arranged at a relatively steep angle to the horizontal.

4. A conveyor as set forth in claim 1 wherein the guide members comprise pairs of complementary rails extending along and above the bank of conveyor rollers and defining the laterally-overlapped paths of travel for the articles.

5. A conveyor as set forth in claim 1 wherein the length of the rollers comprising a series of long rollers following a series of short rollers considered in the direction of feed of the conveyor is less than the length of the rollers comprising the series of long rollers preceding said series of short rollers.

6. A conveyor as set forth in claim 1 wherein the lengths of the rollers comprising the series of both long and short rollers following an offtake chute considered in the direction of feed of the conveyor are less than the lengths of the rollers comprising the series of long and short rollers preceding said offtake chute.

7. A conveyor as set forth in claim 1 wherein the approximate width of the offtake chute corresponds to the difference in length between the short rollers and the long rollers located immediately in advance of the chute.

8. A conveyor as set forth in claim 1 wherein the length of the rollers comprising the final series of long rollers in the bank of conveyor rollers corresponds approximately to the width of a single path of travel for an article and terminates at a final delivery station.
